UNITED STATES PATENT OFFICE.

JOHN B. ADT, OF BALTIMORE, MARYLAND.

IMPROVEMENT IN ROTARY ENGINES.

Specification forming part of Letters Patent No. 146,630, dated January 20, 1874; application filed December 12, 1873.

To all whom it may concern:

Be it known that I, JOHN B. ADT, of Baltimore city, and State of Maryland, have invented a new and Improved Rotary Engine; and I do hereby declare that the following is a full, clear, and exact description of the same, reference being had to the accompanying drawing forming a part of this specification, in which—

Figure 1 is a vertical cross-section. Fig. 2 is a longitudinal vertical section.

The invention relates to means whereby rotary engines may be more conveniently packed, the piston kept always radial to the center of shell, and the usual clapping noise avoided, all as hereinafter more fully described.

A represents a cylindrical shell, having a shaft, *d*, eccentrically journaled therein. With this shaft, and concentric therewith, rotates a circular disk, *C*, having the longitudinal recess *c*, converging to a neck near the periphery, and having in one side of this neck or not, according to the size of the engine, a friction-roll, *b*. E is the steam-chest, having steam-inlet port *e* and exhaust *e'*. Attached to the rotary disk *C* are the two ring-plates *a a*, having the large concentric apertures *a'*, connected by the cross-plate or piston *a''*, flush on the outer surface with the periphery of ring-plates, and made concentric with the shell, so as to turn steam-tight therein. The piston *a''* has an end packing, *a'''*, and, being concentric with the shell, and made in one piece with the ring-plates *a a*, bears always firmly against the inside of the shell. The disk *C*, however, moves up and down on the piston during each rotation, being brought into contact, or nearly so, at the end *e''* of the shortest radius of shell, when the upper end of piston nearly or quite coincides with the circumference of the disk. As soon as the piston reaches the exhaust-port *e'*, the valve *e''* shuts off the steam until it has passed the steam-inlet *e*. I am aware that a

piston sliding in a cavity, *C'*, of revolving disk *C* is not new, but mine is a piston that does not slide in and out of center-piece, but is unchangeable in its relative position to the center of the shell. It thus maintains a continuous perpendicularity to inside of shell, and is enabled without difficulty to work steam-tight. It cannot stick, let steam blow through, or produce noise, because of its being in one solid piece with the plate rings, which move in a circle concentric with the axis of the shell. Another advantage in my mode of operating the disk on the piston and within its ring-plates is, that the eccentricity of disk-center to that of shell may be made greater or less, no guide being required in the disk beyond a recess, *c'*, of adequate depth.

In order to enable the disk *C* to move with as little friction as possible, a roller, *b*, may be journaled in one side of the neck of recess, and made to project a little therefrom, to allow for the variation of the position of the disk *C* to that of the piston *a''*. The latter is thus kept always in the same plane with axis of shell, but never in the same plane with the center of disk, except when at the point *e''*, and diametrically opposite thereto.

It is believed that this engine is much less liable to get out of order by reason of the piston being in one piece with the ring-plates.

Having thus described my invention, what I claim as new, and desire to secure by Letters Patent, is—

The combination with case *A* and the eccentric shaft *d*, that carries the disk *C*, of the ring-plates *a a*, carrying piston *a''*, and slotted to allow the said shaft to move, in the manner and for the purpose described.

JOHN B. ADT.
